UNITED STATES PATENT OFFICE.

EDWARD BAMBAUER, OF VOLTA, CALIFORNIA.

PUNCHING-MACHINE.

971,514.

Specification of Letters Patent.

Patented Oct. 4, 1910.

Application filed January 13, 1910. Serial No. 537,960.

To all whom it may concern:

Be it known that I, EDWARD BAMBAUER, a citizen of the United States, residing at Volta, in the county of Merced and State of California, have invented a new and useful Punching-Machine, of which the following is a specification.

The invention relates to improvements in punching machines.

10 The object of the present invention is to improve the construction of punching machines, more especially that shown and described in Patent No. 940,575, granted to me Nov. 16, 1909, and to increase the power 15 or leverage of the machine, whereby the same may be operated with greater ease and rapidity.

Another object of the invention is to increase the strength and durability of the 20 machine and relieve the same of side strain in the operation of the actuating cam, and to increase the efficiency of the adjustable clamping means for holding the sheet metal or other material operated on.

25 A further object of the invention is to equip the machine with adjustable reversible guides, adapted to enable the material to be readily set in proper position for punching a plurality of rows of holes.

30 With these and other objects in view, the invention consists in the construction and novel combination of parts hereinafter fully described, illustrated in the accompanying drawings, and pointed out in the claims 35 hereto appended; it being understood that various changes in the form, proportion, size and minor details of construction, within the scope of the claims, may be resorted to without departing from the spirit or sacrificing any of the advantages of the invention.

In the drawings:—Figure 1 is a perspective view of a punching machine, constructed in accordance with this invention. Fig. 45 2 is a longitudinal sectional view of the same. Fig. 3 is a transverse sectional view, taken substantially on the line 3—3 of Fig. 2. Fig. 4 is a vertical sectional view on the line 4—4 of Fig. 3. Fig. 5 is a detail perspective view of the punch actuating cam. Fig. 6 is an enlarged rear elevation of the adjustable clamp. Fig. 7 is a longitudinal sectional view of the same. Fig. 8 is a transverse sectional view on the line 8—8

of Fig. 6. Fig. 9 is a similar view on the line 9—9 of Fig. 6. Fig. 10 is a detail perspective view of one of the reversible guides.

Like numerals of reference designate corresponding parts in all the figures of the drawings.

60 In the embodiment of the invention illustrated in the accompanying drawings, the punching machine comprises in its construction a slidable frame 1 and a track 2, designed in practice to be suitably secured to the top 3 of a bench, or other suitable support and to be of a length to accommodate the work to be operated on.

65 The punching machine may be of any size and weight to adapt it for punching holes in various kinds of material, and the track, which may be of any desired length, consists of a vertical flange 4 and a horizontal supporting flange 5, the vertical flange being provided in its upper edge at regular intervals with notches 6, forming teeth having inclined edges and vertical shoulders, adapted to be engaged by a dog 7 of the feeding mechanism hereinafter described. 70 The horizontal flange, which forms a support for the slidable frame 1, is provided at intervals with openings 8, which may be any desired distance apart and which are designed to permit the metal punched from the material to fall through the machine. 75 The horizontal flange is preferably spaced from the upper face of the top 3 of the bench by blocks or washers 9, arranged on bolts 10, or other suitable fastening devices for securing the track 2 to the bench.

80 The slidable frame, which may be constructed of any suitable material, includes front and rear spaced plates 11 and 12, arranged vertically and receiving the vertical flange 4 of the track between their lower 85 portions. The rear plate 12 is provided at its lower end with a forwardly extending horizontal flange 13, which engages beneath the horizontal flange of the track at the back thereof. The front plate 11 is provided at 90 its lower end with a horizontal base 14, arranged upon the horizontal supporting portion of the track and provided at the outer edge thereof with a depending rearwardly extending approximately L-shaped flange 15, 95 engaging beneath the horizontal flange of the track at the front thereof, as clearly illustrated in Fig. 3 of the drawings. By 100 105

this construction the frame of the punch is slidably interlocked with and is adapted to move along the track. The slidable frame is actuated by an upright oscillatory operating lever 16, fulcrumed at an intermediate point in the slidable frame by a pivot 17 and connected above the fulcruming pivot 17 with a cam actuating lever 18 by links 19. The links 19 are spaced apart to receive the upper arm of the operating lever and the cam actuating arm or lever, and they are connected to the said parts by bolts, or other suitable pivots. The lower arm 20 of the operating lever 16 is provided with a pin or pivot 21, arranged in a longitudinal slot 22 of the dog 7. The dog 7, which is provided at its front or outer end with a depending bifurcated engaging portion or tooth 23, straddles the upper edge of the vertical flange of the track and successively engages the shoulders, formed by the notches 6. When the lever is oscillated forwardly in the direction of the arrow in Fig. 2 of the drawings, the slidable frame is advanced along the track, the distance being regulated by an adjustable pin or key 24 and a plurality of perforations 25, which permit the pin to be arranged different distances from the fixed stop 26 for limiting the backward movement of the operating lever. The backward movement of the upper arm or handle portion of the operating lever swings its lower arm 20 forward and advances the dog 7 along the track. The fixed stop 26 is preferably formed by one of the bolts, or other suitable fastening devices for connecting front and rear plates of the slidable frame, spacing sleeves being arranged on the bolts for maintaining the front and rear plates in proper spaced relation.

The punch 27 is mounted in vertically alined guide openings of upper and lower arms 28 and 29 of a bearing bracket or support, which is in the form of a casing, being composed of inner and outer upright members 30 and 31, the horizontal arms 28 and 29 being preferably formed integral with the inner plate or member 30 and located at a point intermediate of the ends thereof and at the lower terminal of the same. The inner member 30 is riveted or otherwise secured to the outer face of the plate 11, and the outer member is secured by screws 32 to the arms 28 and 29, the upper arm being fitted in a groove 33 in the inner face of the outer member 31. The members 30 and 31 are provided near their upper ends with opposite alined bearings for the reception of spaced rounded bearing portions 34 of a punch operating cam 35, arranged above and adapted to engage the upper end of the punch 27, as clearly illustrated in Figs. 3 and 4 of the drawings.

The punch is beveled at its upper end, and the cam, which depends from the pivot,

engages the beveled upper end of the punch in its forwardly swinging actuating movement. The supporting of the outer end of the cam by the outer member 31 relieves the cam and the machine of side strain, and by 70 making the bearing bracket or support of the requisite strength, the machine may be constructed for punching relatively thick sheet metal or other material. The inner and outer members 30 and 31 are provided at the top with suitable oil holes or passages, extending to the bearing openings and hinging the pivot of the cam to be lubricated. The bearing portions 34 constitute an integral pivot, which is also provided with a 80 flattened oblong portion 36, located between the inner and outer plates of the slidable frame and arranged in an opening 37 of the arm or lever 18, which is preferably fixed to the pivot of the cam by a set screw 38. The 85 screw 38 detachably connects the arm 18 with the pivot of the cam, but any other suitable means may be employed for this purpose. The pivot is provided at this side of the arm with a terminal reduction 39, 90 which fits in a bearing opening of the rear plate 12. The terminal portion 39 of the pivot is pierced by a pin or key 40, located at the outer face of the rear plate 12, as clearly shown in Fig. 3 of the drawings. 95 The arm 18 may be of any length to secure the desired leverage or power for operating the punch, and an easy and rapid operation of the same is thereby secured.

The punch is provided at its lower end 100 with a reduced portion 41, which pierces the sheet metal or other work placed in the machine. The base 14 of the slidable frame carries a detachable plate 42, which is equipped with a die 43, having an opening 105 to receive the lower reduced engaging portion of the punch. The punch is removable from the bearing bracket, being detachably retained in place by a pin or key 44, located at the upper portion of the punch and engaged by a coiled spring 45, disposed on the punch and interposed between the pin or key 44 and the lower arm 29 of the bearing bracket. The die, which is constructed of tool steel, or other suitable material, is fixed 110 in an opening of the plate 42, and it projects above the upper face of the same and is supported by a lower washer 46. The die plate 42 is detachably secured to the base 14 by inverted screws 47, piercing the base 14 115 and the plate 42 and having their heads countersunk in the lower face of the former. When it is desired to remove the die and the punch, the slidable frame is disengaged from the track by sliding it off one end 120 thereof. The die 43 and its plate 42 are then detached and the punch may be removed through an opening 48 in the base 14. The opening 48 registers with the openings 8 of the top, as clearly shown in Figs. 2 to 4 in- 125

clusive of the drawings. The die and the punch may be changed for other sizes.

When the handle portion of the operating lever is thrown forward, the pin or pivot moves the distance of the slot 32 before actuating the slide frame, and this independent movement of the operating lever is sufficient to carry the cam from the upper end of the punch and permit the same to be raised clear of the work by the spring before the machine is advanced along the track. The punch is actuated in its operation on the sheet metal or other material during the rearward movement of the upper arm of the operating lever and while the dog is moved forwardly along the track. The dog is maintained in engagement with the upper edge of the vertical flange of the top by means of a spring 49, provided at its upper end with an eye 50 arranged on one of the transverse fastening devices, which connect the front and rear plates of the slide frame. The spring is provided at an intermediate portion with a bend, and its lower portion, which is free, engages the upper edge of the dog near the outer or front end thereof, as clearly illustrated in Fig. 2 of the drawings. This insures a positive engagement between the tooth 23 of the dog 7 and the shoulders formed by the notches of the track.

The punching machine is adapted to operate on sheet metal or other suitable material of any width or length within its capacity, and it is equipped with stationary and adjustable clamps 50^a and 51, arranged in spaced relation and adapted to engage a piece of sheet metal or other material at the opposite sides or ends thereof, the adjustable clamp being movable outwardly by the means hereinafter described to enable any kinks or bends in the sheet metal or other material to be readily stretched out of the same, so that the holes will be punched with absolute accuracy. Also this will prevent any creases or bends in the sheet metal from interfering with the rapid and free operation of the punching machine. Each of the clamps comprises a substantially U-shaped body portion, arranged horizontally and having its upper side bifurcated for the reception of a cam lever 52, provided at its lower end with a cam head 53. The cam head 53 is pivoted in the bifurcation 54 and is adapted to clamp the material firmly against the lower side of the U-shaped body portion. The U-shaped body portion of the stationary clamp 50^a is secured to the bench by screws 55, or other suitable fastening means.

The adjustable clamp is mounted upon a guide 56, approximately L-shaped in cross section and constructed of angle iron or other suitable material and composed of a vertical flange or wing and a horizontal

flange or wing. The horizontal flange or wing, which is secured by screws 57, or other suitable fastening devices to the bench 3, is mounted upon a supporting plate or piece 58, and it is provided at its angle with a groove 59, formed in the lower face of the guide and engaged by a horizontally projecting flange 60 of a plate 61, secured to the rear face of the clamp at the outer end thereof, whereby the adjustable clamp is slidably interlocked with the guide. The clamp is provided at its rear face with a longitudinal groove or recess 62, located at the bottom of the clamp, as clearly shown in Fig. 8 of the drawings, and receiving the vertical flange or wing of the guide 56. The plate 61 is secured by screws or other suitable fastening devices to the adjustable clamp, which is seated upon the horizontal supporting or attaching flange or wing of the guide. The adjustable clamp is provided at the outer end with a horizontal threaded opening 63 and is engaged by a screw 64, mounted upon an adjustable member or support 65, which is slidably interlocked with the guide 56.

The adjustable member or support, which is approximately L-shaped, is slidably arranged upon the guide 56 and is provided at the inner or rear face with a longitudinal groove or recess 66, which receives the vertical flange or wing of the guide, as clearly shown in Fig. 9 of the drawings. The adjustable member 65 is slidably interlocked with the guide by means of a plate 67, secured by screws or other suitable fastening devices to the rear side face of the said member 65, and provided at its lower edge with an inwardly extending horizontal flange 68, which fits in the longitudinal groove or recess 59 of the guide. The opening 63 extends entirely through the outer portion of the adjustable clamp, as clearly shown in Fig. 7 of the drawings, and the screw is swiveled to the upwardly extending portion of the L-shaped adjustable member, being provided with a smooth outer portion 69, which pierces the said upwardly extending portion of the adjustable member. The screw is provided at the inner end of the smooth portion 69 with a collar 70, and its outer end has a head 71, which is bifurcated for the reception of an operating handle 72, secured in the bifurcation by a suitable pivot 73, and adapted to be arranged at an angle 120 to the screw to enable the same to be readily rotated to stretch the material to the desired tension. The vertical flange or wing of the guide is provided at intervals with perforations 74 for the reception of a transverse pin 75, carried by the adjustable member 64 and adapted to secure the latter in fixed relation with the guide. The adjustable member 64 is provided with a transverse opening for the removable pin 75, 130

and in applying the adjustable clamp to the material, the member 64 to which the clamp is connected is adjusted along the guide and is secured to the same by the said pin 65 to effect the preliminary adjustment of the clamp 51. The adjusting screw is then rotated to stretch the material and to effect the pivotal adjustment of the said clamp 51.

The punching machine is equipped with 10 detachable gages 76, consisting of plates provided with vertical slots 77, extending upwardly from the lower edges of the plates to permit the latter to straddle the vertical flange or wing of the track, as clearly 15 shown in Fig. 1 of the drawings. The vertical slot 77 is located at a point between the center of the gage 76 and to one side thereof, so that the distance is greater between the slot and one side edge than the other. The gages are adapted to be placed 20 upon the vertical flange or wing of the track at different points along the same and they present smooth edges or faces to the said flange or wing, and are utilized when 25 it is desired to punch two rows of holes. The material is fitted against the guides, as 30 illustrated in dotted lines in Fig. 1 for arranging the said material in proper position for the first row of holes, and after the same has been punched, the material is removed 35 from the clamps and the gages are reversed to space the material for the second row of holes. In starting the latter, the punch is arranged to operate opposite the intervals 40 of the holes already punched. This will enable two rows of holes to be punched comparatively close to the edge of the material. The gages, however, may be provided with a greater number of slots for enabling two 45 or more rows of holes to be punched.

The machine is arranged for operation by 50 sliding the frame with its punching mechanism back to the end notch or recess, and the dog is engaged therewith. The operating lever is then swung forwardly until the 55 slideable frame is carried forwardly as far as it will go with the one movement of the lever. The gages are then arranged on the vertical flange or wing of the track, one in advance and one in rear of the dog, and the material is fitted against the gages and is engaged by the clamp, the screw of the adjustable clamp being adapted to stretch the material to remove all slack and take out any 60 kinks or bends, which might interfere with the rapid operation of the punching machine or the accuracy thereof. The rearward movement of the upper arm of the operating member advances the dog and simultaneously actuates the punch in the downward movement thereof for engaging the material. The forward movement of the upper arm of the operating lever permits the punch to move upwardly and also advances 65 the slideable frame. The upward movement

of the punch occurs while the pivot 21 at the lower end of the operating lever is traveling rearwardly from the front end of the slot 22 to the rear end thereof, and the forward movement or advancement of the slideable frame 70 does not begin until the punch is entirely clear of the material. The actuating arm of the cam and the operating lever afford a double leverage in actuating the punch in the downward movement thereof and enables the necessary power to be easily obtained for adapting the machine to the character of the work to be performed. 75

Having thus fully described my invention, what I claim as new and desire to secure by Letters Patent, is:—

1. A punching machine including a track, a frame slideable along the track, a punch carried by the frame, an operating lever, means actuated by the operating lever for 85 feeding the frame along the track, and a cam arranged to actuate the punch pivoted independently of the lever and provided with an arm arranged in spaced relation with the lever and connected with and actuated by the same. 90

2. A punching machine including a track, a frame slideable along the same, a punch carried by the frame, an upright operating lever, means actuated by the operating lever 95 for feeding the frame along the track, a cam arranged to actuate the punch and provided with an upwardly extending arm, and a link connecting the arm of the cam with the lever. 100

3. A punching machine including a track, a frame slideable along the same, a punch carried by the frame, an upright operating lever fulcrumed at an intermediate point in the frame, feeding means connected with 105 the lower arm of the lever, a cam for actuating the punch provided with an upwardly extending arm, and a link connecting the arm of the cam with the upper arm of the lever. 110

4. A punching machine including a track, a frame slideably mounted on the track, a punch carried by the frame, an operating lever, a dog pivotally connected to the operating lever and engaging the track, a 115 spring carried by the frame and bearing against the dog for holding the same in engagement with the track, and means operated by the lever for actuating the punch. 120

5. A punching machine including a track, a frame slideable along the track, a punch carried by the frame, an upright operating lever including upper and lower arms, a dog connected with the lower arm of the operating lever, a cam for actuating the punch having an upwardly extending arm connected with the upper arm of the operating lever, and a spring carried by the frame and bearing against the dog for maintaining the same in engagement with the track. 130

6. A punching machine including a track, a frame slidable along the same, a punch carried by the frame, an operating lever fulcrumed in rear of the punch, a cam mounted in the frame above the punch and having an arm connected with the lever, a dog connected with the lever and engaging the track, and a spring located in advance of the cam and bearing against the dog for holding the same in engagement with the track.

7. A punching machine including a track, a frame slidable along the same, a bearing bracket composed of inner and outer members, and connecting arms, said members being provided above the arms with bearings, a punch arranged between the members and guided in the said arms, a cam located between the upper portions of the members and arranged to engage the punch and having a pivot mounted in the said bearings, an operating lever connected with the cam, and means actuated by the operating lever for feeding the frame along the track.

8. A punching machine including a track, a frame slidable along the same, an upright bearing bracket composed of inner and outer members provided at their upper portions with alined bearings, and horizontal arms formed integral with one of the members and secured to the other member, a punch located between the members and guided in the said arms, a cam located above the punch and having a pivot journaled in the said bearings, an arm connected with the said pivot, an operating lever pivoted in the frame and connected with the said arm, and means actuated by the operating lever for feeding the frame along the track.

9. A punching machine including a track, a frame slidable along the track, a detachable punch mounted on the frame, a die located beneath and coöperating with the punch, a removable plate carrying the die and detachably secured to the slidable frame, and means for operating the punch.

10. A punching machine comprising a track provided with teeth, a punch mounted on the frame, clamping means for holding the work, a gage detachably seated on the track and presenting smooth faces to the same and reversible to present different portions to the work, and punch operating mechanism including feeding means engaging the teeth of the said track to move the frame along the same.

11. A punching machine including a track, a frame movable along the track and provided with a punch, clamping means for holding the work, and spaced gages detachably fitted on the track and adjustable to different positions on the same and reversible to present different portions to the work.

12. A punching machine including a track, a frame movable along the track and provided with a punch, clamping means for

holding the work, and a gage having a slot to detachably fit the track, said slot being arranged at a point between the center and one side of the gage and the latter being reversible to present different portions to the work.

13. A punching machine including a track having an upwardly extending flange, a frame movable along the track and provided with a punch, clamping means for holding the work, and a gage provided with a slot to receive the flange of the track and straddling the same.

14. A punching machine including a track having an upwardly extending flange, a frame movable along the track and provided with a punch, clamping means for holding the work, and spaced gages provided with slots to receive the flange of the track and located at a point between the center of the gage and one side, whereby the gages are reversible to present different portions to the work.

15. A punching machine including a track, a frame movable along the track, punching mechanism carried by the frame, a fixed clamp, a guide, an adjustable clamp slidably interlocked with the guide, an adjustable member also slidably interlocked with the guide, means for securing the adjustable member to the guide, and means for adjustably connecting the said member with the adjustable clamp.

16. A punching machine including a track, a frame movable along the track, punching mechanism carried by the frame, a fixed clamp, a guide provided at intervals with perforations, a clamp slidable along the guide, an adjustable member provided with means for engaging the perforations of the guide, and a screw connecting the adjustable clamp with the said member.

17. A punching machine including a track, a frame movable along the track, punching mechanism carried by the frame, a fixed clamp, a guide having an upwardly extending flange and provided with a groove, an adjustable clamp provided with means for engaging the said groove to interlock it with the guide, an adjustable member also having means for engaging the said groove, an adjusting screw connecting the adjustable clamp with the member, and means for adjustably securing the latter to the guide.

18. A punching machine including a track, a frame movable along the track, punching mechanism carried by the frame, a fixed clamp, an approximately L-shaped guide having an upwardly extending flange and provided at its angle with a groove, an adjustable clamp receiving the upwardly extending flange of the guide, a plate secured to the clamp and having a projecting portion fitting in the groove of the guide, an

adjustable member detachably secured to the guide, and a screw for connecting the adjustable member with the clamp.

19. A punching machine including a track, a frame slideable along the track, punching mechanism carried by the frame, a fixed clamp, an approximately L-shaped guide having an upwardly extending flange and provided at its angle with a longitudinal groove, an adjustable member having a longitudinal groove to receive the flange of the guide, a movable clamp also provided with a groove to receive the flange of the guide, plates secured to the movable clamp and to the said member and engaging the groove of the guide for slidably interlocking the movable clamp and the member with the said guide, and means for adjustably connecting the movable clamp with the member.

20. A punching machine including a track, a frame movable along the track,

punching mechanism carried by the frame, a fixed clamp, a guide, a movable clamp slidably interlocked with the guide, an approximately L-shaped member also slidably interlocked with the guide and having an upwardly extending portion, a screw engaging the clamp and having a smooth outer portion piercing the upwardly extending portion of the said member, said screw being provided at its outer end with a head and having a collar spaced from the head, the upwardly extending portion of the member being located between the head and the collar, and an operating handle pivotally connected with the head of the screw.

In testimony, that I claim the foregoing as my own, I have hereto affixed my signature in the presence of two witnesses.

EDWARD BAMBAUER.
